UNITED STATES PATENT OFFICE.

WILLIAM C. STAHL, OF MILWAUKEE, WISCONSIN.

DESIGN FOR A MANDOLIN-BODY.

No. 38,682.

Specification for Design.

Patented July 16, 1907.

Application filed March 28, 1907. Serial No. 365,209. Term of patent 7 years.

To all whom it may concern:

Be it known that I, WILLIAM C. STAHL, a citizen of the United States, residing at Milwaukee, in the county of Milwaukee and State of Wisconsin, have invented a new, original, and ornamental Design for a Mandolin-Body, of which the following is a specification, reference being had to the accompanying drawing, forming part thereof.

Figure 1 is a front view of a mandolin

body showing my new design, the upper portion of the finger board being removed; and Fig. 2 is a side view thereof.

I claim

The ornamental design for a mandolin body, as shown.

WILLIAM C. STAHL.
